UNITED STATES PATENT OFFICE.

DANIEL S. SPEESE, OF DETROIT, MICHIGAN.

KNITTING MACHINE.

Application filed November 8, 1920. Serial No. 422,358.

To all whom it may concern:

Be it known that I, DANIEL S. SPEESE, a citizen of the United States of America, residing at Detroit, in the county of Wayne and State of Michigan, have invented certain new and useful Improvements in Knitting Machines, of which the following is a specification, reference being had therein to the accompanying drawings.

In the art of knitting hosiery circular knitting machines are employed for producing tubular fabric of different weaves and such weaves are characterized by the threads thereof extending in circumferential or longitudinal directions, particularly the latter wherein "chain" stitching produces a hosiery fabric that may be comparatively thin and conformable to various shapes when placed in use. This is especially true in silk stockings and it is a well known fact that when a thread is worn or accidentally severed it will leave a longitudinal gap in the fabric which tends to elongate as the fabric is used. Furthermore, the severing of a longitudinal thread in a chain stitch fabric releases many other threads so that the end of a narrow gap often widens into a large gap or "hole" and this is very pronounced in women's hosiery. When the threads extend in a circumferential direction a somewhat similar gap may occur if the thread is worn or broken and when a hole is produced it is difficult to determine just how large it will eventually be unless immediately mended, to gather or connect the released threads and thus prevent "running" of the hole.

The paramount object of my invention is to provide a fabric so knitted that should one of the threads thereof be worn or broken it will be held against unraveling, thereby preventing a gap or hole that can "run" and temporarily, if not completely, destroy the appearance of the fabric. This object of my invention is attained by a fabric having threads extending in diagonal directions and closely knitted in contradistinction to threads which extend longitudinally or circumferentially of a piece of tubular fabric, and in knitting the diagonally disposed threads they are so interlocked or articulated that it is practically impossible for the end of the

thread to work out of the fabric and leave a gap or large hole. By resorting to knitted diagonal threads it is possible to use a stitching which causes a multiplicity of threads to bind against each other and it is the surface friction of the threads and the many turns or twists of the same that will prevent the end of any release thread from "running" or releasing other threads. In other words a hole in a piece of fabric is only enlarged by being actually worn to such enlargement.

To produce an unraveling piece of tubular fabric such as briefly mentioned above, I employ a novel circular knitting machine, and the machine may be characterized in the following particulars.

First, there are reciprocatory circumferentially arranged needles having hook bills or barbs that are automatically closed by presser members so that the needles may gather, draw, or pull one or more threads into a looped formation, and through another loop. Associated with these needles are sinkers or jacks together with a novel mechanism for operating the sinkers and needles in timed relation.

Second, there are outer and inner oscillatory guides which are circumferentially shiftable about the axis of the machine and a very important feature of the machine is the operating mechanism by which the inner and outer guides are caused to shift about the machine, in contradistinction to the guides of former machines which are circumferentially arranged and simply reciprocate relative to each other without being carried in a circumferential path.

The mechanism employed permits of the inner and outer guides being oscillatory, reciprocated, and bodily shifted circumferentially of the axis of the machine in such timed relation that all of the inner and outer guides may cooperate with the reciprocatory needles in knitting threads into a tubular fabric having an unravable weave.

Third, there is an organization of instrumentalities which cooperate in providing a machine that is compact without being inaccessible when parts of the machine are to be repaired or defective threads removed. On account of the construction of the ma-

chine it is thought best to consider the same under the following captions, namely fabric; reciprocatory needles; sinkers or jacks; needle pressure members; outer guides; and inner guides, together with a resume of the general operation of the machine.

Reference will now be had to the drawings, wherein—

Figure 1 is a vertical cross sectional view 10 of the upper portion of the knitting machine;

Fig. 2 is a horizontal sectional view of the same, partly broken away, and taken on the line II—II of Fig. 1;

Fig. 3 is a similar view taken on the line III—III of Fig. 1;

Fig. 4 is a plan of the machine, partly broken away and partly in section;

Fig. 5 is a horizontal sectional view of the 20 machine, showing the cam lay out and the timed cooperation of various parts of the machine;

Fig. 6 is an enlarged plan of a portion of the machine, showing a few of the sinkers 25 or jacks relative to the reciprocatory needles and a knitted fabric;

Fig. 7 is a side elevation of a ratchet mechanism forming part of the machine;

Fig. 8 is a view of a series of needles 30 and guides showing, on a large scale, the manner in which threads are knitted;

Fig. 9 is a perspective view showing the manner in which a presser member may co-operate with a needle in permitting the 35 needle to draw or pull threads through a loop;

Fig. 10 is a similar view showing the needle at further step in its operation;

Figs. 11 to 15 inclusive are diagrammatic 40 views illustrating the movement of guides and the manner in which threads are knitted;

Fig. 16 is a view of a piece of fabric on an enlarged scale with the fabric stretched 45 or loose to show the manner in which threads are knitted, this view permitting of threads being traced throughout the fabric;

Fig. 17 is a view of a piece of fabric showing one face thereof greatly magnified to 50 illustrate a surface produced by knitted threads; and

Fig. 18 is a similar view of the reverse face of the piece of fabric.

In describing my invention by aid of the 55 views above referred to, I desire to point out that the same are intended as merely illustrative of a machine by which my invention may be put into practice, and I do not care to confine myself to the precise construction and arrangement of parts, other than defined by the appended claims.

Furthermore, the glossary of terms will conform as near as possible to the terminology of the knitting art, but in describing

certain actions of the machine or parts thereof 65 of as being clockwise, counterclockwise; certain threads as being diagonal, and certain elements as thread guides, that such terms are simply for the convenience of describing the machine and its products as shown by 70 the drawings, whereas in actual practice, certain movements may be the reverse of those to be hereinafter described; certain elements may have other mechanical equivalents, and the fabric may have stitches somewhat different, particularly when various 75 grades and styles of hosiery are to be knitted.

As pointed out in the beginning, my machine is of the circular type and since my invention resides in the upper portion of the 80 machine, I have deemed it unnecessary to show all the accessories for the machine, for instance, the thread bobbins and the power for operating the machine, it being understood that all of the missing accessories will 85 be provided in order that the machine may produce fabric in accordance with my invention.

Fabric and its texture.

90

(Figs. 8 to 18 inclusive.)

Opposite faces of a piece of fabric have been greatly enlarged or magnified in Figs. 17 and 18, and in the former it will be noted 95 that the majority of the threads are diagonally disposed or at an angle to an imaginary longitudinal line of the fabric, and this is in contradistinction to threads that have heretofore extended either circumferentially or longitudinally of the fabric when

having a tubular form such as knitted in 100 my machine. The reverse face of the fabric has an overlapped loop conformation and by reference to Fig. 16 it will be noted that each loop is composed of two threads which

more or less coincide by providing loops A and B that may be in parallel relation or one within the other according to the manner in which the threads set when being 110 knitted. The loop B has its end threads C alining and in the same plane as the loop but at an angle to the major axis of the loop, and the adjacent loop A has similar ends D but with said ends at a reverse angle

to the ends of the loop B. The sets of loops are in close formation with the last knitted 115 loop overlapping the previously knitted loops so that the ends C and D of one set of loops may pass through the large end of an adjacent loop and these "passing through" ends will be found in the large end of the loop before the ends of the loop diverge to enter remote loops. Following

out some of the threads in Fig. 16, it will 120 be noted that the diverging ends of loops in one row pass over the loops of an adjacent row and enter the loops of the next

row, there being vertical and circumferential rows of loops with the diagonal threads forming loops in each of the superposed rows and it is in this manner that the threads are diagonally or spirally disposed about a tubular piece of fabric instead of being in lateral or vertical planes relative to the axis of the tubular fabric.

Figs. 16, 17 and 18 clearly disclose texture of the fabric and Figs. 8 to 15 will again be considered in connection with needle and guide operations, as it is some of the guides which conduct threads diagonally of the fabric and in opposite directions, while other needles form the loops, so that should a thread be worn or severed, it will have its ends held by the adjacent loops and be prevented from unravelling. Even should a released thread worm its way out of the loops, there is no wide gap or pronounced hole that will cause other threads to be released and the hole enlarged. This is the great difference between my hosiery fabric and that fabric now used for women's stockings.

Reciprocating needles and the operating mechanism therefor.

(Figs. 1 and 2.)

The reference numeral 1 denotes a pedestal for the lower portion of the machine and detachably connected thereto is a tubular vertically disposed head 2 through which the tubular fabric passes as fast as it is knitted at the upper end of the head, this fabric being weighted, in the usual manner, so that it will pass through the head and permit of knitting operations being carried on above the head.

At the juncture of the pedestal 1 and the head 2 there is an annular support for a cam platform 3 having annular cams 4, 5, 6, 7 and 8, and said cam platform is revolvable and has movement imparted thereto by a driven pinion 9 meshing with a rack 10 carried by the lower face of the cam platform 3.

The head 2 is provided with an integral basin like guide 11 above the platform 3 and slideable on said head above the guide 11 is a needle cylinder 12 provided with depending rods 13 extending through the guide 11 with casters or anti-frictional rollers 14 on the lower ends thereof to ride on the annular cam 4, said cam having two rises or peaks, as shown in Fig. 5, so that the needle cylinder 12 may be raised twice during each rotation of the cam platform 3. The needle cylinder 12 has a detachable clamping ring 15 screwed or otherwise mounted thereon and said ring is connected to the guide 11 by two or more retractile springs 16, the retractile force of said springs 16 maintaining the casters 14 constantly on the

annular cam 4 of the cam platform 3. The clamping ring 15 cooperates with the cylinder 12 in holding the sockets 17 of a multiplicity of circumferentially arranged needles 18, said needles extending upwardly at an acute angle relative to the walls of the head 2. One of the needles is best shown in either Fig. 8 or Fig. 9, where it will be observed that the upper end of the needle has a hook or beard 19 with its bill 20 in proximity to shank of the hook, so as to provide an entrance into the loop formed by the hook end of the needle. The hook or beard is yieldable or resilient relative to the needle shank and may be pressed towards the needle shank to contact therewith, as shown in Fig. 9, and thus close the hook end of the needle, which is employed for loop gathering, as will hereinafter appear.

Sinkers or jacks and the operating mechanism therefor.

(Figs. 1, and 2.)

Fixed on the upper end of the head 2 is a collar 21 having a multiplicity of radially disposed slots 22 through which protrude the hook ends of the needles 18. The lower edges of the slotted collar walls are provided with apertured lugs and pivotally connected to said lugs, as at 23, are a multiplicity of circumferentially arranged sinkers or jacks 24 which are tilttable in unison and are operable in slots of the collar 21. Each jack 24 is somewhat in the form of a bell crank having a short hook shaped arm 25 and a long bearing arm 26, the bearing arm of said jack extending into an annular channel member 27 having depending rods 28 extending through the guide 11 and provided with castors or anti-frictional rollers 29 riding on the cam 5 of the cam platform 3. The castors or rollers 29 are normally retained in engagement with the cam 5 by the retractile force of springs 39 connecting the channel member 27 to the guide 11.

As brought out in Fig. 5 the sinkers or jacks are actuated four times during each rotation of the cam platform 3 and during certain stages of the knitting operation the sinkers or jacks engage the fabric, as shown in Fig. 6, and prevent the uppermost threads of the fabric from slipping upwardly while other portions of the threads are knitted or manipulated.

Presser members and the operating mechanism therefor.

(Figs. 1 and 2.)

The annular upstanding wall 31 of the basin like guide 11 is provided with an inwardly projecting annular flange 32 having radially disposed grooves 33 for presser bars or members 34, and these members have studs 130

35 extending into tangentially disposed slots 36 in an annular member shifting plate 37, said plate being seated on the flange 32 and held thereon by a retaining ring 38, best shown in Fig. 2. One edge of the member shifting plate 37 has a segment rack 39 extending through a slot 40 in the wall 31, and when the member shifting plate 37 is shifted on the flange 32 the presser members 10 34 are simultaneously shifted in radial directions.

The presser members 34 have angular inner ends, as best shown in Figs. 1 and 9, and when the reciprocating needles 18 have crossed or intersecting threads in the hooks thereof, the presser members are adapted to impinge against the hooks 19 and close the bills 20 thereof relative to said needles. This is necessary in order that the needles when being lowered, may pass through previously formed looped portions of the fabric and form another loop, as best shown in Fig. 10. As brought out in Fig. 8 the loops A and B are always in engagement with the reciprocating needle 18 and the previously formed loops are connected by the diagonally disposed threads D and C.

The operating mechanism for radially shifting the presser members, 34 is actuated from the cam 6 and includes the following elements:—Suitably attached to the basin like guide 11 are bearings 41 and 42, the former being at the inner side of the cam 6 and the latter directly above said cam. Pivotally connected to the lower end of the bearing 41 is a segment rack 43 having an anti-frictional roller stud 44 constantly maintained in engagement with the cam 6 by the retractile force of a spring 45 connecting the segment rack 43 to the bearing 41. Meshing with the segment rack 43 is a pinion 46 mounted on the lower end of a shaft 47, journaled in the bearing 42 and the upper end of the shaft 47 has a pinion 48 meshing with the rack 39 of the member shifting plate 37. As brought out in Fig. 5, the presser members are actuated twice during each rotation of the cam 6.

50 *Outer thread guides.*

(Fig. 1 and 3.)

The annular wall 31 of the guide 11 affords a seat for a rotatable horizontally disposed annular lower frame 49 which is retained on the upper edges of the wall 31 by a retaining plate 50 suitably secured to the wall 31. The lower face of the frame 49 has a rack 51 and said rack is adapted to be intermittently actuated by a ratchet mechanism associated with the cam 7, said ratchet mechanism including the following construction.

65 Journalled in the wall 31 is a short shaft 52 having its inner end provided with a pinion

53 meshing with the rack 51 of the lower frame 49. On the outer end of the shaft 52 is a gear wheel 54 meshing with a large gear wheel 55 having its hub portion rotatable on a stud 56 supported from the wall 31. The hub portion of the large gear wheel 55 has an integral ratchet wheel 57 and loose on the stud 56 is an arm 58 provided with a spring pressed pawl 59 normally engaging the ratchet wheel 57. This is best shown in Fig. 7 where it will be noted that the arm 58 has a crank 60 extending into the upper slotted end 61 of a rod 62 slidable in the bearing 42 and has its lower end provided with a castor or anti-frictional roller 63 constantly engaging the cam 7 of the cam platform 3. A coiled retractile spring 64 associated with the bearing 42 and the rod 62 maintains the castor or anti-frictional roller 63 on the cam 7, and by reference to Fig. 5 it will be noted that this cam has a plurality of rises or peaks for actuating the ratchet mechanism and imparting an intermittent movement of the lower frame 49.

On the inner edge of the lower frame 49 are a plurality of posts 65 and suitably connected to said posts is a guide ring 66 which has its inner wall provided with a multiplicity of depending guide bearings 67 and these bearings are set into the inner wall of the ring 66 and detachably retained therein by another ring 68. Holding the ring 68 in place is an upper frame 69 having a portion thereof set in the ring 66 and secured therein by screws, 70 extending into annular groove in the ring 68.

The guide bearings 67 are apertured, as at 71, to permit of threads extending therethrough. The lower ends of said guide bearings are bifurcated and provided with pivot pins for the sockets 72 of outer guides 73. The outer guides 73 are circumferentially arranged and converge inwardly towards the upper end of the head 2 with each guide having an eye in its lower end to receive a thread. The guide sockets 72 have cranks 74 extending into the annular groove 75 of an intermediate frame 76 normally resting on the lower frame 49 and slidable on a plurality of guide pins 77 carried by the lower frame 49.

The intermediate frame 76 is somewhat in the form of a spider and has its peripheral edges resting on an internal rack 78 and retained thereon by segment shaped plates 79 suitably secured to said rack at diametrically opposed points and especially where the rack has sockets 80 fixed to the upper ends of rods 81 slidable in sleeve guides 82 connected to the basin like guide 11. The lower ends of the rods 81 are provided with castors or anti-frictional rollers 83 normally engaging the cam 8 of the cam platform 3. As shown in Fig. 5 the cam 8 has diametrically opposed rises or peaks so that

the intermediate frame 76 may be raised twice during each rotation of the cam platform 3.

So far it will be observed that the lower frame 49 may be intermittently moved in circumferential direction and bodily carry with it the nest of outer guides 73 and that when said guides are at rest the intermediate frame 76 may be raised, by virtue of the cam 8 and the rods 81, to oscillate the guides 73.

Inner guides and the operating mechanism therefor.

(Figs. 1 and 4.)

The upper frame 69 previously referred to has its inner edge provided with converging brackets 84 and pivotally mounted on said brackets are the sockets 85 of circumferentially arranged inner depending needles 86 said needles having the lower ends thereof provided with eyes to receive threads that may pass through guides 87 carried by the guide sockets 85. The inner guides have the lower ends thereof in proximity to the lower ends of the outer guide 73; and the guide sockets 85 have cranks 88 extending into an annular channel member 89 which normally rests on the upper frame 69 but is suitably attached to rods 90 extending through the upper frame 69 and provided with shoes 91 riding on an annular rail 92 supported from and above the intermediate frame 76. It is now apparent that when the intermediate frame 76 is elevated through the medium of the rod 81 and the cam 8 that the rods 90 may slide through the upper frame 69 and elevate the channel member 89, so that the guide sockets 85 will be rocked and the depending inner guides 86 shifted towards the outer guides 73.

In order to impart a circumferential movement to all of the inner guides 86 it is necessary to revolve the upper frame 69, and this is accomplished by providing the outer edges of the upper frame with an internal deep rack 93 with which pinions 94 mesh, said pinions having sliding engagement with the internal rack so that said pinions may be carried by shafts 95 supported by the intermediate frame 76. The shafts 95 are journaled in suitable bearings 96 of the intermediate frame 76 and the lower ends of said shafts have pinions 97 meshing with the racks 78. The bearings 96 may also support an annular thread guide 98 for the threads which pass through the bearings 67 of the outer guides 73.

Remembering that the rack 51 is intermittently moved to bodily shift the outer guides 73 in a circumferential direction; that the intermediate frame 76 is carried in a circumferential direction on the lower frame 49; that the rack 78 is held against circumferential movement by the rods 81,

and that the shafts 95 are carried by the intermediate frame 76 with the pinions 97 meshing with the rack 78, it is apparent that the upper frame 69 will revolve the guide ring 66 in an opposite direction from that of the intermediate frame 76, and it is through this novel mechanism that the inner and outer guides may be bodily carried, step by step, in opposite circumferential directions. The mechanism by which this is accomplished does not interfere with an oscillatory movement being imparted to the inner and outer guides when at rest, and with this understanding of the general construction of the machine the operation will now be described by references to Figs. 1, 5, and 8 to 16 inclusive.

Assuming that all of the guides have been threaded and that a portion of tubular fabric has been previously knitted, as shown in Figs. 6 and 8, and that the machine is in operation, the hook needles 18 are gradually elevated and it is during such elevation that the inner and outer guides 86 and 73 are shifted in a circumferential direction. For instance, by reference to Fig. 11, and the arrows of this figure and Figs. 12 to 15 inclusive, it will be noted that the outer guides 73 may be considered as movable in a counterclockwise direction and the inner guides 86 in a clockwise direction. The ends of the guides 73 and 86 are in proximity to each other in two concentric imaginary circles within a circle formed by the needles 18 and said guides are shifted past each other in a defined direction and for a defined distance, the guides being transferred, in their closed relation from within the circle of the reciprocating needles 18 to without the circle of reciprocating needles. As before stated, this circumferential shifting takes place during the initial upward movement of the reciprocating needles 18 and the result of such circumferential shifting is shown in Fig. 12.

While the reciprocating needles 18 are still moving upwardly the outer and inner guides 73 and 86 are tilted or oscillated in unison and are shifted from positions within the nest of reciprocating needles to positions outside of the nest, as shown in Fig. 13. Such oscillating or tilting of the inner and outer guides carries the threads between the reciprocating needles 18 and crosses the threads on the inner walls or within the nest of the reciprocating needles.

With the reciprocating needles still moving upwardly the inner and outer guides are again shifted circumferentially in opposite directions to cross the threads at the outer walls of the reciprocating needles 18, as brought out in Fig. 14, and the inner and outer guides are again oscillated or tilted and shifted to the original positions inside the path of reciprocating needles, as shown

in Fig. 15. By reference to this figure it will be noted that the threads are crossed at the inner and outer walls of the reciprocatory needles and by this time said needles have been completely raised and the oscillatory inner and outer guides come to rest. It is during this period of rest that the reciprocatory needles are lowered and those cross threads on the outer walls of said needles caused to enter the hooks of said needles, so that the reciprocatory needles on the downward stroke may pull downwardly on the cross threads, as shown in Fig. 10, and form a loop, with the loop passing through a previously formed loop while certain of the threads are held by the inner and outer guides. On completion of a loop, as shown in Fig. 10, the tubular fabric is lowered so that the loops lying over the upper rounded edge of the head 2 will be in position to receive newly formed loops as the operation, just described, is repeated. It has been previously pointed out how the hook bills of the reciprocatory needles 13 are closed to temporarily retain the loops in the hooks while one loop is being threaded through a previously formed loop, after which the hook bills are released so that the loops on the needles may be eventually released to enter into the piece of the fabric.

I attach considerable importance to the manner in which the inner and outer guides are caused to sashay about the reciprocatory needles, particularly in opposite circumferential directions, as it is by such movements that the threads are not only crossed but knitted in diagonal or spiral directions in a tubular piece of fabric, this being in contradistinction to threads which usually extend in longitudinal or transverse directions in a piece of fabric.

Considering the texture or knitted design of a piece of fabric produced by my machine, it may be said that the fabric is composed of transverse rows of "loop-in-loop" thread configurations, each configuration being substantially cordate oblong or oval with one end obtusely pointed. The configurations of one row align with configuration of adjacent rows so that the pointed ends of the configurations overlap the large ends of the configurations, and closely or microscopically viewing one side of the piece of fabric, it presents somewhat of a "shell" appearance. Following out the connections between the configurations or the directions of threads, it will be found that the four threads forming the obtuse end of each configuration extends through the large end of each configuration with the threads extending in diverging directions, across adjacent configurations, to remote configurations, preferably those twice removed in diagonal directions. From another descriptive angle, the threads may be considered as extending

from the small end of a configuration in a transverse row, across adjacent configurations of the same row, to the large ends of the next configurations of the same row, so, that in either instance, threads are crossed on each configuration, besides being crossed between the configurations. This means there is a closely knitted interengagement of threads, one binding by surface friction against the other, and should a thread be severed, broken or worn in two, then the loose ends of the threads will be held in place by friction contact, against drawing or running, and unravelling, because of handling, is effectually eliminated:

By reference to Figs. 17 and 18 of the drawings it will be noted that the vertical rows of thread configurations are closely bound together, with the threads C and D, and extend in diagonal directions from one vertical row, across adjacent rows, to the next rows and in other words alternating rows are tied together so that such vertical rows cannot spread. This is very important for the reason that the thread configurations are crowded, one against the other and should the thread configuration in one of the vertical rows be broken or disrupted, the threads of such broken configuration cannot work out or "run." Those configurations bordering on the broken configuration cannot spread apart by reason of being tied by the diagonally disposed threads and since there is no room for a broken configuration to spread, it is obvious that there can be no "run." Even though a loop is broken or dropped during the knitting, the ends of such loop will be held in place by the cross threads and as long as adjacent loops are not materially separated, other loops will not be dropped or released by the end of the broken loop, therefore the closely knitted texture of the fabric is at all times maintained.

What I claim is:—

1. In a knitting machine of a cylinder type wherein fabric as it is knit by needles about said cylinder passes downwardly along the cylinder and is removed from the lower portion of the machine, a horizontal rotatable cam platform about the machine cylinder adapted for reciprocating said needles, inner oscillatory threaded guides, outer oscillatory threaded guides, means actuated from said cam platform for bodily moving said inner and outer oscillatory guides in opposite circumferential directions to cross threads at the inner and outer walls of said reciprocatory needles, and means actuated from said cam platform adapted to grip certain of said crossed threads and form loops.

2. A knitting machine as in claim 1, characterized by the first mentioned means being intermittently actuated and said inner and

outer oscillatory guides remaining at rest during an actuation of the last mentioned means.

3. A knitting machine as in claim 1, characterized by the last mentioned means including hooks having compressible bills, and additional means movable to and from the hooks for closing the hook bills when one loop is threaded through a previously 10 formed loop.

4. A tubular fabric knitting machine comprising a cylinder, rotatable operating means, inner guides, outer guides, means actuated twice by and during one rotation 15 of said operating means for simultaneously oscillating said inner and outer guides means including a ratchet mechanism actuated by said operating means for intermittently moving said guides in synchronism, but said outer guides in an opposite direction from said inner guides, reciprocating hook needles, means actuated twice by and during one rotation of said operating means for moving said hook needles 20 to and from said inner and outer guides to gather and loop threads held by said inner and outer guides, and means actuated four times by and during one rotation of said operating means and through which 25 said hook needles extend adapted to hold the previously looped threads during the operation of said hook needles.

5. In a tubular fabric knitting machine, the combination of reciprocating needles 30 arranged in a circle, inner and outer oscillatory guides adapted to be simultaneously shifted from within the circle of said reciprocating needles to without the circle thereof, a rack surrounding the outer ends 35 of said outer guides, a rack surrounding the outer ends of said inner guides, means common to said racks adapted to circumferentially move said inner and outer guides to cross threads at said reciprocating needles 40 and between said needles, and means supporting said reciprocating needles and adapted to be actuated in timed relation to said inner and outer guides so that crossed threads of said inner and outer guides may 45 be looped and drawn through previously 50 formed loops.

6. In a knitting machine, which has oscillatory and circumferentially movable sets of guides with which needles cooperate in knitting fabric, a lower frame for circumferentially moving one set of guides, an upper frame for circumferentially moving the other set of guides, means operatively connecting said frames so that one 55 frame may be rotated in an opposite direction from the other frame, and means adapted for simultaneously raising said 60 frames to effect oscillation of said guides.

7. A hosiery knitting machine comprising circumferentially disposed inner guides,

circumferentially disposed outer guides, means including rotatable superposed frames adapted for simultaneously oscillating said guides, means including a differential double pinion connecting said 70 frames adapted to be actuated to cause the sets of guides to be circumferentially shifted in opposite directions, the circumferential and oscillatory movement of said guides causing the threads to be crossed, and hook 75 needles movable to and from said inner and outer guides and adapted to loop crossed portions of said threads carried by said inner and outer guides.

8. In a knitting machine of the cylinder 80 type, a lower frame, an intermediate frame, an upper frame, inner oscillatory guides supported by said upper frame, outer oscillatory guides supported by said lower frame independent of said upper frame, means 85 adapted to move said intermediate frame and cause the guides of the lower and upper frames to be oscillated, rotating means for said lower and upper frames, and needles adapted to cooperate with said inner and outer oscillatory guides.

9. A knitting machine as in claim 8, characterized by the last mentioned means including a vertically disposed mechanism at one side of said lower frame adapted to 95 intermittently rotate said lower and upper frames.

10. A knitting machine as in claim 8, characterized by the frame rotating means including racks and pinions having a differential action relative to said racks for causing said lower and upper frames to 100 rotate in opposite directions.

11. In a knitting machine having needles with some of said needles provided with 105 compressible bills, means adapted to close the needle bills, comprising radially disposed presser members, a rotatable plate on said presser members having pin and slot connection with said presser members 110 adapted for moving said presser members in synchronism, and means including a rack and cam actuated ratchet mechanism for intermittently rotating said plate.

12. In a knitting machine, the combination 115 of circumferentially vertically disposed reciprocating needles, inner guides, outer guides, cranks supporting the lower ends of said inner and outer guides adjacent said needles, superposed annular channel members into which said cranks extend, means adapted for raising and lowering said channel members to cause said guides to be oscillated, and means adapted for rotating said channel members.

13. A knitting machine as called for in claim 12, wherein the last mentioned means includes racks and pinions engaging said racks and causing one rack to turn in an opposite direction from the other rack.

14. In a knitting machine having needles be raised and lowered, and means adapted and inner and outer guides:—means for bodily oscillating and revolving said inner and outer guides relative to said needles, said means comprising racks, differential pinions engaging said racks, one of said pinions being slideable relative to its rack so that said pinion and the other rack may
- be raised and lowered, and means adapted for raising and lowering the rack.
- In testimony whereof I affix my signature in presence of two witnesses.
